his Attorney

UNITED STATES PATENT OFFICE.

THOMAS WALTER FRED, OF CHATTANOOGA, TENNESSEE.

DISPLAY TRAY.

Application filed February 7, 1925. Serial No. 7,641.

To all whom it may concern:

Be it known that I, THOMAS WALTER FRED, a citizen of the United States of America, residing at Chattanooga, in the 5 county of Hamilton and State of Tennessee, have invented certain new and useful Improvements in a Display Tray, of which the following is a specification.

My invention relates to improvements in 10 display trays for sample cases.

In the methods heretofore used, articles such as stockings or the like, were handled and wrinkled so as to destroy their value as samples, which should always be attractive in appearance.

An important object of my invention is 20 to provide a device which will enable stockings and similar articles to be displayed and handled without affecting their appearance, attractiveness or value as samples.

Another object of my invention is the provision of a device of the above mentioned character which will display the stocking or other article to its best advantage.

25 A further object of my invention is to provide a device of this character which will be capable of displaying a great variety of styles, colors, etc., and afford a vivid contrast therebetween.

30 Other objects and advantages of my invention will be apparent during the course of the following description.

In the accompanying drawings, which 35 form a part of this specification, and wherein like characters of reference denote like or corresponding parts throughout the same,

Figure 1 is a perspective view of one of the display trays in its displaying position,

Figure 2 is a plan view of one of the trays

40 with the cover pulled back, and illustrating the position of the article when not being displayed,

Figure 3 is a detail perspective of one of the trays,

45 Figure 4 is an end elevation of the same, and,

Figure 5 is a detail sectional view through a portion of the tray.

In the drawings, wherein for the purpose of illustration is shown a preferred embodiment of my invention, the numeral 50 10 designates a tray preferably rectangular in shape and formed from a sheet of cardboard 11, wood or other suitable material 55 covered with a suitable fabric 12, as for example, velvet, of a soft color such as blue

or green, a reinforcing strip 13 extends across the back of the tray 10 adjacent one of its ends to also serve as a hand hold. Elastic straps 14 extend across the front of 60 the tray and are secured to the back thereof. These straps are spaced from the top and bottom of the tray but arranged adjacent thereto. Secured to the lower edge of the tray is a cover of fabric 16 corresponding to the tray covering, and of the 65 same color.

The articles to be displayed, illustrated as stockings "S", are slipped under the straps 14 and securely held thereby, and 70 preferably overlap each other, thereby allowing a great many stockings to be secured to one tray. These stockings are arranged in pairs of different styles and colors, the stockings in a pair being secured to 75 together at various points by means of threads of silk 15 the ends of which are raveled to form an attractive tuft of brightly colored silk.

It will be seen that the major portion of 80 the stocking is arranged below the lower of the two elastic straps 14, and consequently, when the tray is held vertically, this portion of the stocking will dangle freely with the softly colored cover 16 as a background. They may be handled at will, but will always retain their shape and attractiveness, and cannot become rolled into balls, as has heretofore been the case. When not 85 in use, the stockings are folded upon themselves, over the lower of the straps, as shown in Figure 2, and the cover 16 drawn over them, as shown in Figure 3. Suitable tags 90 17, or the like, indicate the brand of hosiery, manufacturer, etc.

95 These trays may be conveniently carried in any suitable case, the trays being adapted to be arranged one above the other in the case.

While I have shown and described the 100 preferred embodiment of my invention, it is to be understood that various changes in the size, shape, and arrangement of parts may be resorted to without departing from the spirit of my invention or the scope of 105 the subjoined claims.

Having described my invention what I claim and desire to protect by Letters Patent is:

110 1. A stocking display tray comprising a stiff base, elastic straps secured thereto adjacent its top and bottom and adapted to

retain the upper portions of the stockings to be displayed, the major portions of the stockings being free, and a flexible cover secured to the lower end of the base and adapted to act as a supporting background when in its displaying position.

2. A stocking display tray comprising a stiff base covered with a fabric, a reinforcing and gripping strip arranged on the rear side of said base and adjacent its top, transversely extending elastic straps secured to said base adjacent its top and bottom but spaced therefrom and adapted to retain the upper portion of the stockings to be displayed, the major portions of the stockings being free, and a flexible cover secured to the lower end of the base and adapted to act as a supporting background for the stockings when being displayed.

3. A stocking display tray comprising a stiff base, a reinforcing and gripping strip

arranged on the rear side of said base and adjacent its top, transversely extending elastic straps secured to said base adjacent its top and bottom but spaced therefrom and 25 adapted to retain the upper portion of the stockings to be displayed, the major portions of the stockings being free, and a flexible cover of substantially the same size and configuration as the base, secured to the 30 lower end of the base, the stockings being adapted to be folded about the lower elastic strap and arranged wholly upon the base, the flexible cover being adapted to be normally arranged over the base so as to cover the 35 stockings, but being adapted to dangle freely when in displaying position, and to act as a supporting background for the free ends of the stockings.

In testimony whereof I affix my signature.

THOMAS WALTER FRED.
